UNITED STATES PATENT OFFICE.

CHARLES E. SHADALL, OF MILWAUKEE, WISCONSIN, ASSIGNOR TO SHADALL MANUFACTURING COMPANY, OF WAUWATOSA, WISCONSIN, A CORPORATION OF WISCONSIN.

WATER-CLOSET.

1,340,567.

Specification of Letters Patent. Patented May 18, 1920.

Application filed September 18, 1916. Serial No. 120,634.

To all whom it may concern:

Be it known that I, CHARLES E. SHADALL, a citizen of the United States, residing at Milwaukee, in the county of Milwaukee and 5 State of Wisconsin, have invented certain new and useful Improvements in Water-Closets, of which the following is a specification, reference being had to the accompanying drawing, forming a part thereof.

10 The main objects of this invention are to provide within the structure of a water closet bowl, means for its ventilation; to facilitate installation of the ventilating means with the bowl; to prevent disagreeable noise in the ventilating connections due to longitudinal vibrations in the air entraining passage or other causes; to provide for varying the air entraining fluid jet according to varying conditions such as the pressure of the fluid supply; to avoid as far as possible exposed metal parts and joints, which are objectionable; and generally to improve the construction and operation of 20 devices of this class.

25 It consists in the peculiar construction, arrangement and combination of parts as hereinafter particularly described and pointed out in the claims.

In the accompanying drawing like characters designate the same parts in the several figures.

30 Figure 1 is a vertical section from front to rear of a water closet bowl embodying the invention; Fig. 2 is a vertical section on an enlarged scale of the aspirator constituting a part of the invention; Fig. 3 is a horizontal section on the line 3—3, Fig. 2, of the aspirator nozzle; Fig. 4 is a cross section on the line 4—4, Fig. 2; and Fig. 5 is an 40 axial section of a modified form of the nozzle.

45 Referring to Fig. 1, *a* designates a water closet bowl formed around the top with a flushing rim *b*, of the usual or any suitable construction, and in the lower part with a water trapped or sealed outlet passage and soil pipe connection *c*. It is provided with a rearwardly projecting housing or extension forming an aspirator chamber and a 50 foul air outlet passage *d*, which at one end has an air inlet and drain opening into the bowl above the water seal therein and at the other end an outlet opening for the connection of a ventilating pipe *e*, by which 55 foul air and odors drawn from the bowl

through said passage are conducted to any convenient point and discharged into the atmosphere outside of the building in which the closet is installed or discharged into a ventilating shaft or flue with which the 60 building is provided.

The wall of the housing or extension forming the aspirator chamber and passage *d* is formed integrally with the bowl *a*, and completely surrounds said chamber and passage between the air inlet and outlet openings at its inner and outer ends, thus concealing the aspirator and avoiding exposure to view of metal parts except the pipe connections required to operate the aspirator 70 and carry off foul air.

A pipe *f* connects the flushing rim or passage of the bowl with a flushing tank or other source of water supply, controlled by a valve in the usual or any suitable manner. 75

To draw foul air and odors from the bowl and force them out through the ventilating pipe *e*, an aspirator *g* is provided in the chamber *d* of the bowl.

The aspirator may be constructed in various ways, one of the preferred forms being shown in Figs. 2, 3 and 4. In accordance with the form illustrated, it comprises a T-shaped casing consisting of a nozzle tube or body *h*, and a valve case *i*, which may be 85 formed as shown, integrally therewith, and at right angles or transversely thereto. The valve case, as shown in the present instance, is formed with a flange *j*, and provided at its lower open end with a cap nut *k*, by which 90 the aspirator is secured in an opening formed in the lower wall of the chamber *d* of the bowl, as shown in Fig. 1. A pipe *l*, for supplying water, steam or other fluid under pressure, to operate the aspirator, is connected with the valve chamber by the cap nut *k*. At its upper end the valve chamber 95

communicates with the nozzle tube or body *h* through a port which is normally closed by a valve *m* guided therein and having 100 a stem *n* extending upwardly through the bore of the nozzle tube and provided at its upper end with a head or guide *o*, fitted in an opening in the upper side of the nozzle tube. The valve is closed and held normally against its seat in the upper part of the chamber or case *i*, by a spring *p*. The nozzle tube or body *h*, which is supported by the valve case *i* within and lengthwise of the chamber *d*, is open at the ends and 110

provided at the end toward the bowl with a screw cap or plug *q*, and at the opposite end with a tip or cap *r*, threaded thereon and formed with a jet orifice *s*, which is directed toward the outlet opening from the chamber *d* into the ventilating pipe *e*.

- To vary or adjust the size of the jet issuing from the orifice *s*, or the amount of fluid passing through the nozzle according to varying conditions, such as widely different pressures of the fluid supply, the nozzle is provided with a flanged thimble *t*, threaded in the end of the tube or body *h* to which the tip or cap *r* is applied. The outer end of the thimble is split and the tip or cap *r* which fits over it, is tapered so that by screwing the tip or cap more or less upon the tube or body *h*, the bore of the thimble may be contracted more or less as desired.
- The nozzle is provided with means for imparting a spiral, whirling or rotary movement to the fluid jet issuing from the orifice *s*, whereby an even and symmetrical jet is produced, a whirling or spiral movement is imparted to the entrained air, and disagreeable noises resulting from vibrations of the air in the chamber *d* and pipe *e*, or from other causes, are prevented. This may be accomplished in different ways, for example, by spiral or oblique holes *u*, formed in a partition or cross wall of the tube *h* between the valve *m* and the thimble *t*, as shown in Figs. 2, 3 and 4.

- To prevent clogging or obstruction of the jet orifice *s* and of the passage through the thimble *t*, the nozzle is provided with a clearer, consisting of an axially movable rod or wire *v*, passing from the jet orifice through the thimble and a central opening in the partition or cross wall of the tube *h* and connected at its inner end with a yoke *w*, guided in and movable lengthwise of said tube. The valve stem *n*, passing through an elongated opening in the yoke *w*, is provided with an incline *x*, which by engagement with the yoke, shifts the rod or wire *v* backward, withdrawing it from the jet orifice *s* when the valve *m* is opened, thereby loosening and dislodging any dirt or obstruction which may have been caught in said orifice or in the bore of the thimble *t*. The clearer rod or wire *v* is moved in the opposite direction when the valve *m* is closed, by a spring *y*, interposed between the cap or plug *q* and the yoke *w*.

- The valve *m* may be opened manually by a handle, or by a connection with the hinged seat *z* of the bowl, as shown. For this purpose a lever 2, mounted on the nozzle and engaging at one end with the head or guide *o* on the valve stem, is connected at the other end by a rod 3 passing through an opening in the upper wall of the chamber *d* with a rearwardly projecting arm 4 on the seat, as shown in Figs. 1 and 2.

The ventilating pipe *e* into which the aspirator nozzle is directed from the chamber *d* of the bowl, is preferably made of elbow-shape and formed at the bend opposite the orifice *s* with a concave recess or cavity 5, which facilitates separation of water from the air when the aspirator is supplied with water or steam. The pipe *e* is formed in the lower side of its horizontal branch with a longitudinal groove or channel 6, through which water caught in the cavity or recess 5, drains back into the chamber *d* and thence into the bowl.

Referring to Fig. 5, showing a modification of the nozzle, a tapering tip *r'* in which the jet orifice *s'* is formed, is screwed into the tube or body *h* of the nozzle and is provided at its inner end with a plug 7 removably threaded therein and formed with spiral or oblique holes *u'*, by which a rotary or whirling movement is imparted to the jet issuing from the orifice *s'* and to the air entrained by the jet.

In the operation of the apparatus, when the valve *m* is opened, water or other fluid under pressure is admitted from the pipe *l* to the nozzle and issuing therefrom through the orifice *s* in a jet or spray, entrains air therewith through the chamber *d*, thereby drawing foul air and odors from the bowl and forcing them out through the pipe *e*. When water or steam is used to operate the aspirator, the water or condensed steam directed into the cavity 5 at the bend of the pipe *e*, is separated from the air and drains back through the channel 6 in the lower side of the pipe into the chamber *d* and thence into the bowl above the water seal.

A rotary or whirling movement is imparted to the water or other fluid under pressure in passing through the spiral or oblique holes *u* or *u'*, thereby causing a rotary or whirling movement of the jet issuing from the orifice *s* or *s'* and of the air entrained therewith through the chamber *d* and adjacent end of the ventilating pipe *e*, tending to produce an even or symmetrical and more effective air entraining jet and preventing the noise resulting from longitudinal vibrations of the air in the ventilating pipe or from other causes.

With the opening and closing of the valve *m* the clearing rod or wire *v* is shifted lengthwise of the nozzle by the action of the incline *x* and the spring *y* on the yoke *w*, thereby loosening and dislodging any dirt or foreign matter which might otherwise clog or obstruct the jet orifice or passage leading thereto.

The term "bowl" as herein used, is intended to include a urinal or other similar closet fixture.

Various changes in the details of construction of the apparatus may be made without departure from the principle and scope of

the invention as defined in the following claims.

I claim:

- 5 1. A water closet bowl provided on one side with an extension forming an aspirator chamber and housing having a foul air inlet and drain opening at one end into the upper part of the bowl and an outlet opening at the other end adapted for the connection therewith of a ventilating pipe, the wall of said housing being formed integrally with the bowl and completely surrounding said chamber between the openings at its ends.
- 10 15 2. The combination of a water closet bowl provided with an extension forming an aspirator chamber and housing having a foul air inlet and drain opening at one end into the upper part of the bowl and an outlet opening at the other end adapted for the connection therewith of a ventilating pipe, the wall of said housing being formed integrally with the bowl, and completely surrounding said chamber between the openings at its ends, a spray nozzle inclosed in said chamber and housing and directed toward said outlet opening, and a valve controlled water supply connection with the nozzle.
- 20 25 30 3. A water closet bowl formed integrally with an aspirator chamber and housing opening and adapted to drain into the bowl and having an external outlet opening for connection with a ventilating pipe, an open-

ing for a water supply connection and an 35 opening for a valve operating connection.

4. The combination of a water closet bowl formed integrally with an aspirator chamber and housing opening into the bowl and having an external outlet opening, and an 40 aspirator comprising a casing inclosed in said chamber and housing and having a valve controlled water supply connection and a jet orifice directed toward said outlet opening.

45 5. The combination of a water closet bowl formed integrally with an aspirator chamber and housing opening into the bowl and having an outlet opening, an opening for a water supply connection and an opening for 50 a valve operating connection, an aspirator comprising a casing inclosed in said chamber and housing and formed with members at an angle to each other one of which is secured in the water supply opening and the 55 other is provided with a nozzle directed toward the outlet opening, a valve within said casing controlling the supply of water to the nozzle, and a valve operating connection passing through the opening therefor in 60 said housing.

In witness whereof I hereto affix my signature in presence of two witnesses.

CHARLES E. SHADALL.
